TO FRANK NOVOTNY AND JOSEPH KASTOHRYZ.

DRIVING MECHANISM FOR WASHING-MACHINES.

1,340,329.

Specification of Letters Patent.

Patented May 18, 1920.

Application filed July 2, 1917. Serial No. 178,174.

To all whom it may concern:

Be it known that I, HERMAN C. DOMAN, a citizen of the United States, and resident of Oshkosh, in the county of Oshkosh and 5 State of Wisconsin, have invented new and useful Improvements in Driving Mechanism for Washing-Machines, of which the following is a description, reference being had to the accompanying drawings, which are a 10 part of this specification.

The invention relates to driving mechanisms and more particularly to a washing machine driving mechanism.

The invention is designed to provide a 15 driving mechanism of simple and efficient construction for oscillating the pounder shaft in opposite directions while moving it up and down and consists in the arrangement and combination of parts hereinafter 20 set forth.

In the drawings:

Figure 1 is a view of the device embodying the invention, showing it applied to a washing machine, parts being shown in section; 25

Fig. 2 is a detailed sectional view taken on the line 2—2 of Fig. 1;

Fig. 3 is a view taken on the line 3—3 of Fig. 1.

30 In the drawings the numeral 4 represents the tub or receptacle of the washing machine, 5 the usual cover, 6 the pounder of any suitable construction, 7 the pounder shaft and 8 the bearing bracket for the 35 pounder shaft mounted on the cover and to which the shaft actuating means, herein-after described, is connected.

The pounder shaft 7 is provided with a helical guide groove 9 in which is partially seated a ball 10 which is mounted in a transverse threaded bore 11 in the bracket 8 and retained in the groove by a set screw 12 in threaded engagement with said bore. With 40 this construction it will be observed that the 45 position of the ball 10 is fixed with respect to the bracket so that when the shaft 7 is moved up and down, the ball being seated in the groove 9, will cause said shaft with its pounder to be partially turned in one direction on the downward movement of the 50 shaft and to be partially turned in the opposite direction during the upward movement of the shaft.

Means are provided for moving the 55 pounder shaft up and down consisting of

an operating lever 13 provided with a handle 14 and connected to the pounder shaft 7 and to the bracket 8. The lever 13 is pivotally connected at one end to links 15 which are pivotally connected to an upwardly extending arm 16 on the bracket 8. The lever 13 is pivotally connected intermediate its ends to the shaft 7 by means of pointed set screws 17 mounted in bifurcated portions 18 of the lever and engaging in recesses 19 60 in a sleeve 20 secured to the pounder shaft 7 by a collar 21. A washer 22 is interposed between the sleeve 20 and the shoulder portion 23 of the pounder shaft 7 and serves as a stop to limit the downward movement of 65 the shaft. This connection permits the pounder shaft 7 to turn with respect to the operating lever.

To facilitate the quick return movement of the pounder shaft I provide a pair of 70 spaced apart springs 24 connected at one of their ends to knobs 25 carried by a shaft 26 pivotally mounted in the lever 13 and connected at their other ends to knobs 27 secured to a rod 28 pivotally mounted in the 75 arm 16 of the bracket. The springs are held in line with the knobs by means of rods 29 secured to the knobs 25 and projecting into bores 30 in the knobs 27.

With this construction when the operator 80 presses down on the handle 14 and thereby moves the lever 13 down against the pressure of the springs 24 the shaft 7 is moved down and turns as previously described, thus moving the pounder 85 down against the clothes and partially rotating it and on the release of pressure upon the handle the shaft 7 moves upwardly moving the pounder upwardly and turning it in the opposite direction. The collar 22 acts 90 as a stop to limit the downward movement of the shaft and the pounder itself acts as a stop to limit the upward movement of the shaft with respect to the bracket 8.

It will thus be seen that a very simple and 100 efficient mechanism has been provided for moving the pounder shaft to operate the pounder.

What I claim as my invention is:

1. A washing machine comprising a centrally bored bearing member, a shaft journaled in said bore for an oscillating and reciprocating movement, a lever having one end pivotally connected with the washing machine and an operating handle formed on 110

its other end, a sleeve member freely rotatably mounted on the upper end of said shaft, and trunnions connecting said sleeve member with said lever intermediate its ends 5 to pivotally connect said lever and shaft and at the same time permit the free rotation of the shaft.

2. A washing machine comprising a centrally bored bearing bracket, an arm carried 10 thereby and directed upwardly and outwardly from the center of the bracket, a shaft journaled in the bore of the bracket for an oscillating and reciprocating movement, a lever pivotally connected with the 15 outer end of said arm and having an opening therein intermediate its ends, a reduced portion formed on the upper end of said

shaft, a sleeve member rotatably mounted on the reduced portion of said shaft, a collar member mounted on the shaft between the 20 shoulder formed by said reduced portion and the sleeve member, a securing collar for maintaining the sleeve member on said shaft, said sleeve member being disposed within the opening in said lever, and adjustable 25 pointed trunnions carried by said lever and engaged in diametrically opposed recesses in said sleeve member to pivotally connect said lever with said shaft, said collar member forming a stop to limit the downward 30 limit of movement of said shaft.

In testimony whereof I affix my signature.

HERMAN C. DOMAN.
